L. J. WAHL

ELECTRIC CLIPPER

Filed Oct. 14, 1919

FIG 1

FIG 2

INVENTOR.
Leo J. Wahl,
BY Walter N. Haskell,
his ATTORNEY.

UNITED STATES PATENT OFFICE.

LEO J. WAHL, OF STERLING, ILLINOIS.

ELECTRIC CLIPPER.

Application filed October 14, 1919. Serial No. 330,547.

To all whom it may concern:

Be it known that I, LEO J. WAHL, a citizen of the United States, residing at Sterling, in the county of Whiteside and State of Illinois, have invented certain new and useful Improvements in Electric Clippers, of which the following is a specification.

My invention relates to electric clippers especially designed for use in barber shops, though it is suitable for use in a variety of other ways where hair cutting devices are employed, such as the clipping, trimming, or shearing of animals, and similar uses.

One object of my invention is the production of a device in which all of the moving elements as well as those elements that produce the motion are a part of the clipper which is handled by the operator.

Another object of my invention is the provision of means whereby the motion which is imparted to the clipper portion of the mechanism may be produced electro-magnetically without the necessity of using any form of circuit breaker or interrupter.

Other objects of the invention will appear and be described in the specification.

The novelty of my invention will be hereinafter more fully set forth and specifically set out in the claims.

In the accompanying drawing:

Fig. 1 is a plan view of a device embodying my invention, the casing being shown in section.

Fig. 2 is a longitudinal sectional side elevation of Fig. 1, the section being taken through the solenoids.

The same characters of reference are used to indicate identical parts in both figures.

I am aware that electrical clippers have been produced wherein the reciprocating motion of one of the clipper blades has been derived from an electric motor through the medium of a flexible shaft and suitable motion translating apparatus; also clippers in which the moving clipper blade has been operated electro-magnetically, the pulsations in the current being produced by or through the medium of a vibrator or current interrupter which alternately opens and closes the circuit through the electric-magnets, and it is to overcome the disadvantages of the above mentioned forms of clippers that my invention has been conceived.

Those structures which employ an electric motor and a flexible shaft with the delicate translating mechanism in the clipper han-

dle are easily rendered inoperative and require considerable attention to maintain them in proper operating condition, while those structures which operate electro-magnetically on a direct current require a vibrator to produce the interruptions to the flow of the current and at the normal voltage available for this class of work it has been found exceedingly difficult to produce a vibrator which would not be rendered ineffective through the arcing caused by this voltage. It is to overcome the disadvantages inherent in both the above mentioned types and to produce a device which will operate continuously and successfully without either a flexible shaft and its accompanying mechanism or a vibrator and its accompanying troubles, that my invention is aimed.

For purposes of illustration and to show a form of structure embodying my invention 1 represents a metallic casing of suitable size and shape to be grasped by the operator, such casing forming the handle by means of which the instrument is guided and controlled while in use. Electro-magnetic coils 2 and 3 are mounted on a suitable core 4, and suitably secured to one of the walls of the casing, the terminals of the coils being connected as by leads 5 and 6, through the medium of any suitable switch, with a source of alternating current supply such is used generally in connection with the ordinary incandescent electric lights, the connection to the source of current supply being by means of the ordinary plug and socket, where it is desired to so install the device that it may be readily disconnected, or in any other manner desired.

A bar 8 which either carries or comprises an armature for the electro-magnet 3 and 4 and which is mounted, as at *a* in the handle portion 1, extends to and is operatively connected with the moving clipper blade 9, which rests upon and is held in contact with the stationary clipper blade 10, the latter being secured to the handle portion 1.

Any suitable means such as a spring 11 may be employed to normally hold the bar 8 away from the ends of the core of the electro-magnets so that when an alternating electric current is passed through the electro-magnets the bar 8 will be caused to vibrate, thereby causing the movable clipper blade 9 to a reciprocate with relation to the stationary clipper blade 10.

While the construction shown in Fig. 1

includes a pivotal mounting for the bar 8 and a spring 11 for normally holding this bar away from the coils, it is apparent that the bar 8 may be of such size and material 5 as will constitute a properly proportioned spring, and be fastened solidly to some portion of the casing 1, the bar being so mounted that it will normally occupy its proper position away from the coils, being intermittently attracted thereto when an alternating 10 current passes through the coils.

It is to be noted that the weight of the moving parts of the clipper must be so proportioned with relation to the attraction of 15 the electro-magnets that the rate of vibration of the bar 8 is different from the cycle of the alternating current for the reason that if the rate of vibration of the bar coincides with the current cycle each succeeding alternation 20 of the current will add its resultant magnetic pull to the already harmoniously vibrating bar, thus causing progressively increased over-running of the device when operating under no load, and a lessening of 25 the normally full stroke under load, where- as if the normal rate of vibration of the bar is different from the current cycle, each maximum magnetization or saturation of the coils will produce a full stroke of the

clipper blade without the danger of over- 30 running under no load conditions and under running under full load.

Having thus fully described my invention, I claim:

1. In a mechanism of the character described the combination of an alternating current electro-magnet, an armature for the electro-magnet, and vibrating at the rate of alternations of the operating current, and a mounting for the armature imparting thereto vibratory characteristics different from the alternations of the operating current to prevent overrunning.

2. In a mechanism of the character described the combination of a frame or case, 45 an alternating current electro-magnetic device carried thereby, an armature adjacent the alternating current electro-magnetic device and vibrating at the rate of alternations 50 of the operating current, a mounting for the vibratory armature and comprising in part means for imparting vibratory characteristics to the armature different from the rate of alternations of the operating current to prevent overrunning, and a member 55 moved by the armature.

In testimony whereof I affix my signature.

LEO J. WAHL.
